(57) **CLAIM**

The ornamental design for a “handle for mobile computer,” as shown and described.

DESCRIPTION

FIG. 1 is a top, front and left side perspective view of a handle for a mobile computer showing my new design; FIG. 2 is a bottom, front and right side perspective view thereof;

FIG. 3 is a top, rear and right side perspective view thereof; FIG. 4 is a front view thereof;

FIG. 5 is a rear view thereof;

FIG. 6 is a left side view thereof;

FIG. 7 is a right side view thereof;

FIG. 8 is a top view thereof;

FIG. 9 is a bottom view thereof;

FIG. 10 is a top, front and left side perspective view thereof with a mobile computer; and,

FIG. 11 is a bottom, front and right side perspective view thereof with a mobile computer.

The broken lines illustrate environmental subject matter which forms no part of the claimed design.
